DRAFTING INSTRUMENT

Gail C. Abruzzi and Marie T. Abruzzi,
Chicago, Ill.

Application March 5, 1945, Serial No. 580,976

3 Claims. (Cl. 33—80)

1

The present invention relates generally to a drafting or engineering instrument of a simple and economical construction and which secures to a maximum degree accuracy in operation.

One of the primary objects of the present invention is to provide a novel and improved construction of drawing instrument which reduces to a minimum the flexing of the straight edge thereof as is usually occasioned by the straight edge of the parallel link type of drafting instrument heretofore used.

A further object of the invention is to provide a novel, simplified and easily operated construction of a drafting instrument which combines the ruling edges of a protractor and parallel moving straight edge on a drawing board which simplifies the manipulation of the instrument and accurately maintains the ruling edges against flexing or yielding movement in the use and operation of the same.

These and other objects are accomplished by providing a construction and an arrangement of the various parts in the manner hereinafter described and particularly pointed out in the appended claims.

Referring to the drawings:

Fig. 1 is a fragmentary top plan view of a parallel moving straight edge in combination with our improved drafting instrument attached thereto; and

Fig. 2 is a cross sectional view taken on the line 2—2 in Fig. 1.

In illustrating the preferred form of our invention we have shown the same in connection with a more or less conventional parallel moving bar or straight edge generally indicated by the reference character 10. This parallel bar or straight edge is preferably, though not necessarily, made of dove-tail cross section main bar 11 and a lower flat and relatively thinner bar 12 secured together by suitable countersunk screws 13. The upper and lower portions of the bar are provided with the conventional tapered drawing edges 14. The opposite ends of the bar 12 are connected by means of clamping plates 15 to cables 16 (only one of which is shown in the drawings). The cables are trained about pulleys (not shown) attached to the drawing board or table in the manner well understood in the art to maintain the straight edge 10 parallel to the upper and lower edges of the drawing board in its movement up and down in the operation of the use of the instrument in a manner well understood in the art. Slidably mounted for longitudinal movement on the straight edge 10 is a

base member 17 which has its lower end provided with a transverse dove-tailed recess 18 which is complementary to the dove-tail bar 11 of the straight edge 10. Located between the lower beveled edge of the dove-tail bar 11 and the lower beveled edge of the dove-tail recess 18 in the base member 17 is a friction plate 19. Extending through the lower edge of the base member 17 and in threaded engagement in suitable apertures therefor are a plurality of horizontally spaced set screws 20 which have their inner ends adapted to seat in recesses 21 in the plate 19 for preventing the displacement of the plate 19. These screws 20 also permit the adjustment 5 between the base member 17 and the straight edge for taking up the wear when wear occurs. All of these parts may be made of any satisfactory material such as aluminum, wood or plastic or other material which proves satisfactory 10 for the particular purpose or function. The upper portion of the base member 17 is in the form of an annular collar as shown at 22. The annular collar 22 forms in effect a vertical bore 23 extending therethrough. The collar 22 is provided with an internal annular recess 24 located 15 at the center thereof. Located in the vertical bore 23 of the collar 22 is an oscillatable knob or hand grip 25. The hand grip 25 is provided with an annular tapered flange 26 which is adapted 20 to rest or seat on the upper surface of the annular ring 22 of the base member 17. The lower portion of the hand grip has a cylindrical portion or hub 27 which protrudes through the vertical bore 23 of the annular ring 22 and terminates 25 at a point flush with the bottom of the annular ring 22. Secured to the lower surface of the projecting cylindrical portion 27 of the knob 25 is a disc or plate 28 which is secured thereto by means of countersunk screws 29. Formed integrally with the plate 28 is a laterally 30 projecting arm 30 to which is secured by means of screws 31 the usual tapered edge ruling bar or ruler 32. Formed integrally with the plate 28 and projecting upwardly adjacent the arm 30 35 and at right angles with respect thereto is a second arm 33 to which is secured by means of screws 34 a second tapered ruling edge or ruler 35. The ruling edge 35 is therefore located at ninety degrees or right angles with respect to the ruling edge 32. This protractor and ruling edge are frictionally locked in certain positions by spring actuated plungers generally indicated 40 by the reference character 36 located in suitable vertical bores in the hub portion 27 of the knob 25 so that the lower curved ends of the plungers

may seat themselves in suitable curved depressions in the circular plate 28 when the ruling bar 25 reaches the ninety degree position or the position shown in Fig. 1 of the drawings. Mounted in the annular recess 24 and frictionally engaging the vertical hub portion 27 of the knob 25 is an arcuate friction bar 37. Located in the outer periphery and at the center of the arcuate friction bar 37 is the circular recess 38 in which the lower end of an adjustable thumb screw 39 is seated. The thumb screw 39 is mounted in threaded engagement in a threaded aperture 40 formed in one side of the annular ring 22 of the base member 17. The protractor in this instance is provided with the usual graduated scale showing the angular magnitude about the upper surface of the annular member 22 as shown generally at 41 for permitting the ruling edges 32 and 35 to be adjusted at various angles.

Summarizing the advantages and functions of operation of our improved drafting instrument, it will readily be seen that by attaching the base member 17 directly to the parallel moving straight edge or bar 19 and associating the protractor and ruling edges thereof directly with the base member, we have effected a simple, economical and rigid structure and one which reduces to a minimum the flexing of the parts so that accuracy can be procured in the operation and use of the instrument. It will also be noted that by providing the plate 19 with the adjustable screws 20 for taking up the wear when wear occurs between these operative parts, we have provided means for maintaining the instrument at maximum efficiency. It will also be noted that by attaching a protractor and ruling edge directly to the parallel moving bar, the overhanging parts such as occasioned by the conventional parallel link drawing instrument is eliminated so that no parts thereof interfere with the operation or complete view of the drawing.

While in the above specification we have described one embodiment which our invention may assume in practice, it will, of course, be understood that the same is capable of modification and that modification may be made without departing from the spirit and scope of the invention as expressed in the following claims.

What we claim as our invention and desire to secure by Letters Patent is:

1. A drafting instrument comprising a straight edge bar, a longitudinally extending member of

dove-tail cross section secured to said bar, a base member having a dove-tail recess complementary to and slidably on said member, a friction plate carried by said base member and engageable with the dove-tail edge of said longitudinal extending member, and means extending through said base member and engageable with said plate for varying the friction thereon and for retaining said plate in position.

10 2. A drafting instrument comprising a drafting straight edge bar, a longitudinally extending member of dove-tail cross section secured to said bar, a base member having a dove-tail recess complementary to and slidably on said member,

15 a friction plate positioned between said member and base, and means for varying the pressure on said plate for retaining said plate in said base.

3. A drafting instrument comprising a drafting straight edge bar, a longitudinally extending member of dove-tail cross section secured to said bar, a base member having a dove-tail recess complementary to and slidably on said member,

20 an adjustable friction plate between the dove-tail edge of said bar in said base member, an annular ring formed integrally with said base member,

25 a hand grip mounted on said ring, a disc secured to the lower side of said hand grip, angularly disposed ruling members secured to said disc, an arcuate friction member carried

30 by said ring and engageable with said hand grip and a thumb screw mounted on said ring and engageable with said friction member for adjusting the frictional tension thereof.
